DESIGN FOR A SUCTION PATTER

Florence N. Lewis, New York, N. Y.

Application August 19, 1933, Serial No. 49,060

Term of patent 7 years

To all whom it may concern:

Be it known that I, FLORENCE N. LEWIS, a citizen of the United States, residing at New York city, in the county of New York, and State of New York, have invented a new, original, and ornamental Design for Suction Patters, of which the following is a specification, reference being had to the accompanying drawing, forming part thereof.

Figure 1 is a view in plan of one face of my suction patter.

Figure 2 is a view of the suction patter handle, and

Figure 3 is a view in plan of the opposite face of the suction patter.

I claim:

The ornamental design for a suction patter, as shown.

FLORENCE N. LEWIS.
